UNITED STATES PATENT OFFICE

163,490

GRINDING MACHINE

Sidney H. Springman, Torrance, Calif.

Application December 1, 1949, Serial No. 6,364

Term of patent 3½ years

(Cl. D37—1)

To all whom it may concern:

Be it known that I, Sidney H. Springman, a citizen of the United States and resident of Torrance, California, have invented a new, original, and ornamental Design for a Grinding Machine, of which the following is a specification, reference being had to the accompanying drawing, forming a part hereof.

Figure 1 is a front perspective view of a grinding machine showing my new design; and

Figure 2 is a rear elevational view thereof.

I claim:

The ornamental design for a grinding machine, substantially as shown.

SIDNEY H. SPRINGMAN.
